UNITED STATES PATENT OFFICE

127,268

DESIGN FOR A SHEET METAL PRESSURE CONTAINER FOR GASES, VOLATILE LIQ- UIDS, AND THE LIKE

Harry C. Beardman, Chicago, Ill., assignor to Chi-
cago Bridge & Iron Company, a corporation of
Illinois

Application March 17, 1941, Serial No. 99,659

Term of patent 14 years

To all whom it may concern:

Be it known that I, Harry C. Beardman, a citizen of the United States, residing at Chicago, in the county of Cook and State of Illinois, have invented a new, original, and ornamental Design for a Sheet Metal Pressure Container for Gases, Volatile Liquids, and the like, of which the following is a specification, reference being had to the accompanying drawing, forming a part thereof, in which:

Fig. 1 is a view in side elevation of the article, showing my design, Fig. 2 is a top plan view, and Fig. 3 is a bottom plan view.

I claim:

The ornamental design for a sheet metal pressure container for gases, volatile liquids, and the like, as shown.

HARRY C. BOARDMAN.
